HOSPITAL SCREEN-CABINET

Dorothy D. Stowell, Hurst, Tex.

Application June 30, 1958, Serial No. 51,591

Term of patent 14 years

(Cl. D33—19)

Fig. 1 is a perspective view of the hospital screen-cabinet embodying my new design;

Fig. 2 is a front elevation thereof; and

Fig. 3 is a side elevation thereof.

I claim:

The ornamental design for a hospital screen-cabinet, as shown.
